UNITED STATES PATENT OFFICE.

JOHN W. BURT, OF CASCILLA, MISSISSIPPI.

DESIGN FOR A COLTER ATTACHMENT FOR PLOWS.

SPECIFICATION forming part of Design No. 29,547, dated October 25, 1898.

Application filed September 30, 1898. Serial No. 692,343. Term of patent 7 years.

To all whom it may concern:

Be it known that I, JOHN W. BURT, a citizen of the United States, residing at Cascilla, in the county of Tallahatchie and State of Mississippi, have invented a new and original 5 Design for Colter Attachments for Plows, of which the following is a specification.

My invention relates to a design for colter attachments for plows, which is represented 10 in the accompanying drawings, in which—

Figure 1 is a perspective view of a colter attachment embodying my invention, looking 15 at it from the inner side. Fig. 2 is a perspective view looking at it from the opposite side. Fig. 3 is a top plan view.

My design consists of the horizontal portion A, having the vertical elongated openings B and a notch C at one side and at a 20 point opposite the middle elongated opening.

Depending from this plate and at one edge 20 thereof is an arm D, having at each side a groove E and a vertical slot F. The grooves E at each side coincide or register with the central elongated opening B and with the notch C at one side of the horizontal portion 25 or plate A.

Having thus described my invention, what I claim, and desire to secure by Letters Patent, is—

The design for a colter attachment, substantially as herein shown and described.

In testimony whereof I have hereunto set my hand in the presence of two subscribing witnesses.

JOHN W. BURT.
